Patented April 30, 1940. Serial No. 202,142. Filed April 15, 1938.

This invention relates to means for identifying documents, such as bank checks, and other like documents, and has for its object the provision of means and methods whereby the signatures of individuals on a check, as payer, payee, or endorser, or in any other important capacity, may be doubly identified and verified.

UNITED STATES PATENT OFFICE

2,198,802

SIGNATURE IDENTIFICATION FOR DOCUMENTS

James J. Brady, Jersey City, N. J.

Application April 15, 1938, Serial No. 202,142

7 Claims. (CL. 283—7)

The present invention relates to bank checks and papers of identification and other like documents, and has for its object the provision of means and methods whereby the signatures of individuals on a check, as payer, payee, or endorser, or in any other important capacity, may be doubly identified and verified.

To this end a paper, such as a check, or the like, is provided with spaces, which are located adjacent the signature spaces, or lines, whereby the signor of such paper may impress, visibly, his finger print or mark adjacent his signature. This feature is admittedly old and well known in this art, and is not claimed herein, as a novel feature. What is new is in the provision of means, on the document, or check itself, whereby the signor, or the individual signing, witnessing or endorsing the document will be provided with a suitable, convenient means, provided on the document itself, whereby he may coat the finger used for fingerprint identification, without having recourse to other external sources, with a fingertip impression coating of color, which may be transferred and impressed upon the associate signature spaces, thereby to create a double identity means, which includes a finger print of the executor of the document, as well as his signature.

The present invention, therefore, includes the provision, on a document, identification paper, or deed or check, the inclusion, of finger print spaces, located adjacent the signature lines, of a non-smudging, color finger impression spot, whereby the party signing the document will find a convenient means, upon said document to color the desired section of his or her identifying finger prints, which are to be transferred and impressed in the spaces associated with the signature spaces to thus impress upon said document the true impression of any finger of the signor of the document.

This feature provides means whereby a signor of a document may find, conveniently located upon a document, check, deed or other legal script, a means whereby his or her identity may be doubly identified. For instance the signor of a check may adopt a system of using only the thumb print of the right hand on checks, and may, in the signing of deeds, use the thumb of the right hand, and in signing of other important, or legal documents use other fingers, on either of the right or left hands, on predetermined classes of documents, such as contracts, bills of sale, and the like, the selection, and adherence to such predetermined selection of finger identification being

entirely at the determination of the individual, who signs the document.

The foregoing and other features of advantage will be apprehended, as the herein description proceeds, and it will be obvious that some modifications may be made in the herein disclosed features, without departing from the spirit hereof, or the scope of the appended claims.

In the drawing accompanying, Fig. 1 is a front view of a document, in the present instance, shown as a check; and Fig. 2 is the obverse, or rear view of the check of Fig. 1.

The check, as shown in Fig. 1, front view is printed in the usual form and includes the bank name, spaces for the sum to be paid, and the line for signature of the payor.

Adjacent the line for signature of the payor is located a space B, outlined by a border line as shown, or without an outlined border, wherein may be impressed a finger print, which when associated with the signature of the payor constitutes a double identification of the executor of the document, or payor.

On the face of the document, Fig. 1, at H, or on the obverse side of the check, at G, Fig. 2, there is provided an associate color spot, printed on or otherwise arranged, upon the document, comprising a combination of a bonding material, meltable at body heat, such as a wax, or like material, which contains and bonds coloring matter, such as lamp black, iron oxide, or similar coloring material, which when the finger of the signor of the document is pressed thereon, and is softened sufficiently, by body temperature, to coat the whorls or loops of the signor's finger and permits the transfer of the colored finger tip impression to the space B, adjacent the signature line A, Fig. 1.

There is no material difference, whether the finger coloring spots G or H are on either the front or rear face of the document. The important feature is the provision of such finger coloring means impressed upon the document, available for instant use by the executor of the document, for the purposes herein set forth.

A further improvement is in the provision of means for additional signatures and finger imprints spaces on the obverse surface of the document, as shown in Fig. 2, wherein finger print spaces C, D, E and F are shown located at the adjacent signature or endorser lines a, b, c and d. In these supplemental, endorsing, or witness lines, the signor may color his endorsing finger print by pressing upon the color spots G and H, and then impressing his or her endorsing finger print

adjacent the associate signature lines. Thereafter, the signor signs the signature space associated with the finger impression receiving area.

Having thus described the invention what is claimed is:

1. A bank check provided on its front face with a place adapted to receive the signature of the payor; lines outlining a space adjacent to said place adapted to receive a finger print; and a color spot larger than a finger print and comprising a mixture of a wax meltable at body heat, and a coloring matter, which when a finger pressed thereon long enough to melt said material will adhere to the finger and may be transferred to the paper in said space.

2. A blank check provided on its back face with a plurality of places each adapted to receive the signature of an endorser; lines outlining a space adjacent to each of said places adapted to receive a finger print; and a color spot on said back separate from said spaces and larger than a finger print and comprising a mixture of a wax meltable at body heat, and a coloring matter, which when a finger pressed thereon long enough to melt said material will adhere to the finger and may be transferred to the paper in any of said spaces to form a finger print therein; said mixture being sufficient to supply coloring matter to provide prints for each of said spaces.

3. A piece of paper provided on its face with a color spot larger than a finger print and comprising a mixture of a wax meltable at body heat, and a coloring matter, which when a finger pressed thereon long enough to melt said material will adhere to the finger and may be transferred elsewhere to form a finger print.

4. A device consisting of a one-piece single thickness single sheet of paper free of attachments and having on one face a place adapted to receive a signature; means on said same face designating a finger print space adjacent to said place; and a color spot on said same face additional to said space and comprising non-corrosive, moisture and light proof non-smear-

ing coloring matter which when a finger is pressed thereon will melt and adhere to the finger and may be transferred to the paper in said space to form a finger print in the space, whereby said matter may be adhered transferred and applied without turning the paper over during the process and without means separate or additional to the paper and without danger of loss, of or the expense of, such additional means; said matter being non-transferable at ordinary temperatures and except when melted.

5. A device consisting of a one-piece single thickness single sheet of paper free of attachments and having on one face places respectively adapted to receive different signatures; plural means on said same face respectively designating finger print spaces respectively adjacent to said places; and a color spot on said same face additional to said spaces and comprising non-corrosive, moisture and light proof coloring matter which when a finger is pressed thereon will melt and adhere to the finger and may be transferred to the paper in said space to form a finger print in the space, whereby said matter may be adhered to different fingers and transferred and applied to said spaces respectively without means additional to the paper and without turning the paper over during the process.

6. A device consisting of a sheet of paper having on one face a place adapted to receive a signature; means on said same face designating a finger print space adjacent to said place; and a color spot on said same face additional to said space and comprising coloring matter which when a finger pressed thereon will melt and adhere to the finger and may be transferred to the paper in said space to form a finger print in the space.

7. A device consisting of a sheet of paper having thereon a finger-print space; and a color spot on said face additional to said space and comprising coloring matter which when a finger is pressed thereon will melt and adhere to the finger and may be transferred to the paper in said space to form a finger print in the space.
